(57) CLAIM

The ornamental design for a shoe upper, as shown and described.

DESCRIPTION

FIG. 1 is a front perspective view of a shoe upper showing my new design;

FIG. 2 is a side view thereof;

FIG. 3 is a rear perspective view thereof;

FIG. 4 is an enlarged view of FIG. 1 with unclaimed subject matter omitted;

FIG. 5 is a front perspective view of a shoe upper showing an alternative embodiment of my new design;

FIG. 6 is a side view thereof;

FIG. 7 is a rear perspective view thereof; and,

FIG. 8 is an enlarged view of FIG. 5 with unclaimed subject matter omitted.

The photographic area is claimed. The broken lines immediately adjacent to the photographic area represent unclaimed boundaries of the design. The broken lines showing the remainder of the shoe are for environmental purposes only and form no part of the claimed design.
